[57] CLAIM

The ornamental design for a suspended fireplace grate, as shown and described.

DESCRIPTION

FIG. 1 is a perspective view of a suspended fireplace grate showing my new design;

FIG. 2 is a side elevational view thereof, the opposite side being identical in appearance;

FIG. 3 is a reduced front elevational view thereof, the rear being identical in appearance and the broken-line showing of the fireplace enclosure being for illustrative purposes only, and forming no part of the claimed design; and

FIG. 4 is a perspective view of an alternate embodiment thereof.

Fig. 1

Fig. 2

FIG. 3

FIG. 4
